Homer Bradford 2 3 FIG. 8.

Norma Geiser

Inventor.

5. Thomas H. Melish,
by John Elias Jones,
attorney.

UNITED STATES PATENT OFFICE.

THOMAS G. MELISH, OF CINCINNATI, OHIO, ASSIGNOR TO THE BROMWELL BRUSH & WIRE GOODS COMPANY, OF CINCINNATI, OHIO, A CORPORATION OF OHIO.

WIRE STRUCTURE.

950,236.

Specification of Letters Patent. Patented Feb. 22, 1910.

Application filed October 3, 1907. Serial No. 395,793.

To all whom it may concern:

Be it known that I, THOMAS G. MELISH, a citizen of the United States of America, and a resident of Cincinnati, in the county 5 of Hamilton and State of Ohio, have invented certain new and useful Improvements in Wire Structures, of which the following is a specification.

This invention relates to wire-structures 10 and more especially to those used in the construction and manufacture of rat-traps, grading-screens for sand and the like, and its object is to provide a strong and durable rib that is adapted to be interlocked with 15 and engaged by mesh and binding wires in a ready and effective manner.

The invention consists in certain novel 20 features of the construction, combination and arrangement of the several parts of the improved wire-structure, whereby certain important advantages are attained and the device is made simpler, cheaper and otherwise better adapted and more convenient for use in rat-traps, sand-screens and 25 the like, all as will be hereinafter fully set forth.

The novel features of the invention will be carefully defined in the claim.

In the accompanying sheet of drawings 30 illustrating my invention, Figure 1 is a plan view of the wire-structure embodying my invention in one form, such as is well adapted to use in a rat-trap; Fig. 2 is a transverse diagraphic view of a rat-trap embodying my invention in its construction; 35 Fig. 3, a longitudinal elevation, taken on the dotted-line a , a of Fig. 1 but on a larger scale, clearly showing my invention herein as it appears when the parts are interlocked 40 for use; Fig. 4, a fragmentary elevation of one end of the rib seen in Fig. 3, such rib forming the principal feature of my invention herein and the interlocking or intersecting wires being omitted in this view for 45 the purpose of clearness in showing the vertical notches or seats in the rib for the intersecting mesh-wires; Fig. 5, a transverse section of the rib and the intersecting wires, taken on the dotted-line b , b of Fig. 3, and 50 showing said rib in what may be regarded as its preferred form for both rigidity and strength; Fig. 6, a plan view of one end of a sheet-metal blank having transverse elongated openings or slots made therein, such

blank being the one used in forming the said 55 peculiar rib of my wire-structure; Fig. 7, a transverse diagraphic series of various forms of rib constituting my invention herein, each of such ribs having the loops and the vertical notches therein for the reception of the 60 intersecting tie and mesh wires but having various formations of sides and base portions and each rib showing therein a cross-section of a round interlocking tie-wire, a length or fragment of the usual binding- 65 wire being also shown interlocked in place in said varied series of ribs, and the preferred form of rib seen in Fig. 5 being also shown in this view; and Fig. 8, a view similar to Fig. 7, but showing flat interlocking trans- 70 verse tie-wires instead of the round ones seen in said Fig. 7.

In these views, 1 represents the ordinary mesh-wires, 2 the tie or binding-wires and 3 the ribs or strengthening portions of the 75 structure. The said mesh-wires intersect the said tie-wires and ribs and thereby form a wire-structure suitable for use in connection with the manufacture or building of rat-traps, grading-screens, or the like, Fig. 2 80 being a diagraphic view of the rat-trap structure in my preferred form. Each rib 3 is composed of a single strip of sheet-metal α having a series of parallel transverse elongated openings or slots 4 made therein and 85 adapted to be bent longitudinally along its center to form a series of loops 5, such loops being a suitable distance apart and separated by open notches formed by said slots 4 and such loops being designated by the same numeral 4. The longitudinal side edges of the strip of sheet-metal are preferably bent inwardly toward each other as shown at 6 in Fig. 5, and then bent outwardly into the bases or flanges 7 as also seen in said Fig. 5. It is 90 obvious that the loops 5 may be circular or rectangular in cross-section, as shown in Figs. 7 and 8, respectively, to accommodate tie-wires of either round or rectangular cross-section, respectively, as shown in said Figs. 100 7 and 8. The round wire is adapted for use in connection with structures wherein it is not necessary to turn sharp corners or corners of very short arc, such round wires being somewhat stiffer and less flexible than 105 the rectangular ones, and such rectangular ones being sufficiently flexible and pliable to take around sharp and short-arc corners in

the operation of making up my wire-structure into rat-trap and other forms of articles of manufacture.

In Figs. 7 and 8, I have shown several series of ribs that are hollow structures that have loops or eyes of both circular and rectangular cross-section, the loops of such ribs having side extensions that may simply taper inwardly, or lie at right-angles, or that may 5 be bent toward each other inwardly, or bent away from each other outwardly, or that may be bent inwardly and then downwardly and outwardly, all to suit the purpose for which the structure is to be used, some structures requiring a very stiff rib while others require a less stiff and rigid rib-frame.

In making up my wire-structure, I take a parallel series of ribs and wind or otherwise lay a series of parallel, suitably spaced 20 mesh-wire in the open notches 4 of the loops or tubular portions of said ribs, then I insert a tie-wire in the loop portion of each rib, such tie-wire passing through said loops and bearing firmly on the mesh-wires that 25 are seated in the bottoms of said open notches, thus firmly interlocking said mesh-wires with the ribs that intersect them. The act of passing or inserting said tie-wires through the hollow ribs is very simple and 30 can be very expeditiously done, the inserting end of each tie-wire being preferably pointed or tapered, as seen in Figs. 1 and 3, if the tie-wires are round ones, so that the inserting ends of said tie-wires can freely 35 pass over the mesh-wires seated in the said open notches and thereby not come into obstructing contact with said mesh-wires. The flat or rectangular-cross-section tie-wires are readily inserted in the rectangular-cross- 40 section loops, seen in Fig. 8, without beveling or pointing the inserting-ends thereof.

The preferred form of loop-rib seen in Fig. 5, wherein either a round or rectangular loop may be used, has the flanges 7 to 45 form a base therefor, such flanges providing a substantial backing for the mesh-wires 1, all the tie-wires and mesh-wires being snugly and tightly interlocked with the ribs so that no part of the mesh-wires adjacent said ribs

can be forced laterally out of its place in 50 the notch of the rib to unduly separate or part the parallel series of such mesh-wires. Thus no undue openings at either side of the ribs can be ordinarily made in the mesh-wires for the escape or passing of anything 55 through the mesh-wires in any irregular or undesired manner.

In Fig. 1, I have shown how the mesh-wires are wound in progressive or spiral form customary in rat-traps, the notches in 60 the parallel series of ribs being out of line to suit the pitch of such spiral winding of the mesh-wires. In grading-screens, the mesh-wires would be straight across and the notches in the several ribs in line with each 65 other, as is obvious.

The opposite ends of the ribs and the tie-wires are suitably set or fastened in place, as are also the opposite ends of the mesh-wires whether for rat-trap or grading-screen use 70 but it is not deemed necessary herein to show any particular manner of fastening the ends of the wire-structure.

I claim:—

As a new article of manufacture, an intersecting-wire and parallel continuous-rib structure comprising a series of parallel ribs each formed of a blank elongated-strip of flat sheet-metal having a longitudinal series of transverse, parallel slots made equidistant 80 apart therein between the longitudinal straight edges thereof and such transversely-slotted blank being longitudinally struck up along its central portion to produce an alternating series of short, connected, circular 85 eyes or loops and narrow deep openings or seats, a series of parallel mesh-wires engaging the bottoms of said deep openings or seats and a series of parallel tie-wires respectively surmounting and intersecting said 90 mesh-wires in said deep openings or seats and engaging said circular eyes or loops for interlocking the said ribs in place.

THOMAS G. MELISH.
